UNITED STATES PATENT OFFICE.

OTTO B. DREUSIKE, OF SAN FRANCISCO, CALIFORNIA, ASSIGNOR TO UNITED STATES METAL PRODUCTS CO., OF SAN FRANCISCO, CALIFORNIA, A CORPORATION OF CALIFORNIA.

SWING-SASH ADJUSTER.

Application filed September 23, 1926. Serial No. 137,192.

This invention relates to adjusting devices for swingingly mounted window sash, and especially to such devices which combine a sliding and pivotal action and are provided with a sliding shoe which guides a minor extension of the sash at one side of the pivot along the window frame while the major extension swings away from the frame in opening the window.

10 The object of my invention is to provide automatic means on such swingingly mounted sash which will partially lock the sash in a predetermined open condition, or that is, will provide a definite position of greater stability, 15 at which the sash will usually be permitted to remain by anyone opening the sash, so that most of the windows in a building when opened for ventilation will be opened to the same angle, and thus a building equipped 20 with such sash will present a neater appearance from the outside when many windows are opened, as against the present appearance where such swingingly mounted sash project at all angles from a building, thereby creating a most unsightly appearance.

In the drawings hereto I have shown my invention as applied to a common form of sliding shoe window mounting and have illustrated it in place on steel frame and sash, tho 30 it is to be understood that its use on any construction of sash or with other specific form of swinging sash mountings is optional.

The views of the drawings show in Fig. 1 a vertical section of a portion of a steel sash and adjacent part of the window frame fitted 35 with sliding shoe type mounting embracing my improvement. Fig. 2 is a plan view of the sash portion of Fig. 1 and Fig. 3 is a rear elevation of the sash portion and a section of the frame portion.

In further detail the figures show at 1 the side wall of a window frame with a sash 2 swingingly mounted thereon, in this case the sash being of the transom variety swinging 45 outwardly at the bottom.

The pivotal mounting of the sash which is supposed to be repeated at opposite edges of the sash, the only one mounting is here shown, comprises a lever 3 pivoted to the frame at 4 and to the sash at 5 and the upper end of the sash pivoted at 6 to a shoe 7 adapted to frictionally engage and slide along a channel formed by the frame 1 so that in swinging the lower end of the sash outwardly the action of

the link 3 will pull the shoe and upper end of 55 the sash downwardly.

The pivot 6 is a rod extended so as to be 60 slideable in the arms of a bracket 8 secured to the sash, and the shoe is secured to the end of the pivot rod and maintained under resilient pressure against the frame channel by means of a heavy spiral spring 9 reacting between an arm of the bracket and a shoulder 6' on the rod.

Thus far, this is known construction and 65 would provide no especial position of the sash for ventilation as the shoe is free to slide downwardly until the sash projects at substantially right angles to the frame.

However, I provide a resilient extension 70 from the shoe in the form of a flat spring 10 secured to the shoe as by a screw 11 and the spring is formed with a rounded shoulder 12, and which is arranged to press against the sides of the frame conjointly with the shoe 75 tho with less pressure since it is of a predetermined resiliency and therefore able to act independent of the strong spiral spring 9 which actuates the shoe.

At some predetermined point along the 80 frame channel in which the shoe slides is formed a recess or indentation as at 13, in the present instance by means of a hole punched through the inner steel layer 1 of the frame but closed over by the second or outer steel 85 member 1' of the frame which in the steel construction under consideration are welded together as a unit to make the complete frame.

This recess 13 is not large enough for the shoe 7 to fall into it but permits the shoe passing 90 thereover. The rounded shoulder 12 of spring 10, however, will snap into it in passing and also snap out of it if a little extra force be applied to operating the window sash.

However, since a decided click will be noticed by a person opening the windows when this point is reached, and also since the sash is more stable and not easily displaced from this point it is manifest that most windows 100 when opened will be permitted to remain at this point of greatest stability and with the result of giving most of the windows opened for ventilation the same angular extension from the building.

I prefer to arrange an auxiliary spring or resiliently actuated device such as the small spring 10 rather than round the edges of the

shoe itself so that it could fall into the depression 13, for the reason that the powerful spring action usually required on the shoe would be too great and make it too difficult to swing the sash from the intermediate position as determined by the depression, besides would cause undue wear on the shoe in rising in and out of the depression even though the edges of the same were rounded.

10 It is of course evident to any skilled mechanic, without further illustration, that instead of rounding the shoulder 12 of the spring the edges of the depression or recess 13 may be rounded, or both may be rounded.

15 It is further evident that the mountings as described are equally applicable to transoms swinging inwardly or outwardly, or to the casement type of sash as they only differ in the direction of swinging; also, that while 20 I show but one embodiment of the invention, any modifications thereof coming within the scope of the invention are intended to be covered by the appended claims.

I claim:

- 25 1. A sash of the outwardly swinging type linked adjacent one end to a window frame and provided at the other end with a guiding shoe adapted to slide along the frame when swinging the sash upon the link, means for resiliently urging said shoe against the frame, and a resiliently actuated detent secured to said shoe cooperating therewith adapted for bringing increased frictional resistance against swinging of the sash at an intermediate predetermined point in its movement.
- 30 2. A swingingly mounted sash of the character described provided with a guiding shoe slidable along a guide on the window frame, a depression in said guide and an auxiliary 35 device secured to and projecting in advance of the shoe also slidable along said guide and resiliently actuated so as to spring into said depression, said depression being in an intermediate position along the guide so as to permit adjustment of the sash beyond it in both directions and when engaged by said

device to retain the sash in intermediate angularly open position.

3. A swingingly mounted sash of the character described provided with a guiding shoe slidable along a guide on the window frame as the sash is swung, a spring resiliently urging said shoe against said guide, a depression in said guide and a second spring projecting from the shoe arranged with a portion to bear against the guide and enter and leave the depression in passing thereover when swinging the sash.

4. A swingingly mounted sash of the character described provided with a shoe slidable along a guide on the window frame, means for resiliently forcing said shoe against the guide, inferior resilient means associated with the shoe also pressing against said guide, and a depression in said guide into which said inferior resilient means is adapted to enter and leave upon passing thereover in swinging the sash.

5. In a swingingly mounted sash of the character described, a window frame, a link pivotally connecting one end of the sash with the frame, a guide on the frame, a shoe in the sash slidable along the guide as the sash is swung, said shoe being secured to a rod axially slidable in a bracket secured to the sash, a spring arranged to force said shoe against the guide, and a flat spring projecting from said shoe and having means thereon adapted to resiliently engage a depression in said guide.

6. A swinging window sash mounting including a sash and a frame to which the sash is pivotally connected to swing open and closed, a friction shoe attached to the sash and slidable along the window frame as the sash is swung, and means on said frame localized at one intermediate point only in the travel of said shoe along said frame arranged to bring increased frictional resistance to the sliding of the shoe at said point.
